UNITED STATES PATENT OFFICE

2,568,728

WIPER FOR FLOATING ROOF TANKS

Fred L. Goldsby and Clifford M. Orr, Chicago, Ill.,
assignors to Chicago Bridge & Iron Company,
a corporation of Illinois

Application February 14, 1947, Serial No. 728,468

1 Claim. (Cl. 220—26)

1

This invention relates to a floating roof tank, and more particularly to a means for excluding moisture from the space between the inner sides of the tank and the sealing shoes thereof.

Liquid storage tanks having a floating roof are customarily provided with a plurality of shoes supported by the roof and adapted to slidably contact the inner walls of the tank. Generally, a flexible seal is provided between the shoes and the edge of the roof to seal the annular space therebetween. While the shoes are held against the inner tank walls with some pressure, it is impossible to make the contact air-tight or water-tight. Consequently, water often seeps into the tank through the space between the shoes and the wall, which water contaminates the product stored in the tank, and is particularly undesirable with dehydrated products. When floating roofs are used in a severe climate, such water is apt to freeze and obstruct the movement of the shoes upwardly and downwardly against the wall, or even to freeze them solidly against the sides of the tank.

We have invented a means for preventing water from reaching the space between the shoe and the wall which comprises broadly a wiper constructed of resilient material which is adapted to be urged against the side wall above the shoe, which not only prevents moisture from entering the space between the shoe and the wall, but also effectively wipes off moisture clinging to the walls upon upward movement of the shoe.

The invention will be described as embodied in the drawings in which:

Fig. 1 is a side elevation of a portion of the side walls of a floating roof tank and a portion of the shoes therein and including our invention;

Fig. 2 is a vertical section along lines 2—2 of Fig. 1; and,

Figs. 3 and 4 are taken like Fig. 2 and show modifications of the invention.

Referring now to the drawings, 10 indicates the side wall of a liquid storage tank, a shoe 11 of usual construction is supported by the floating roof of the tank and urged against the side walls of the tank by means not shown herein, it being understood that our wiper may be used with any usual form of shoe and hanger. A flexible seal 12 is attached to the upper portion of the shoe and extends therefrom to the roof to seal the space between the shoe and the roof. In the embodiment shown in the drawings, the flexible seal is held against the shoe by means of a fabric clamp 13. Attached to the fabric clamp by means of bolt 15 is a resilient bracket 16 which extends

2

upwardly therefrom to a point a short distance above the upper portion of the shoe. A wiper 17 is attached to the bracket by means of a bolt 18, and thereby urged against the tank wall. 5 The wiper is made of resilient material, preferably an abrasion resistant synthetic rubber, and is provided with a plurality of integral flexible fingers 19. The fingers are constructed so that they will flex upwardly or downwardly against 10 the inner wall of the tank with vertical movement of the shoe. The wiper, of course, extends about the entire periphery of the tank and effectively prevents moisture running down the sides of the tank from reaching the space between the 15 shoe and the roof. Furthermore, upward movement of the shoe carries the wiper before it and cleans the side walls from any clinging moisture. An annular flexible sealing member 20 extends about the tank and is adapted to seal the space 20 between the wiper and shoe to exclude moisture from that space. In the embodiment shown in Fig. 2, the flexible sealing member is attached to the wiper, being held between it and the flexible bracket, and is clamped by the fabric clamp 25 13 against the flexible seal 12 which in turn is pressed against the shoe. In the embodiment shown in Fig. 3, the sealing member is an integral extruded tail extending downwardly from the wiper and held against the flexible seal by 30 means of the fabric clamp. In the embodiment shown in Fig. 4, the lowermost finger 19 of the wiper is wedged between the flared upper edge of the shoe and the side of the tank to effect a seal.

While we have shown and described certain embodiments of our invention, it is to be understood that it is capable of many modifications. Changes, therefore, in the construction and arrangement may be made without departing from the spirit and scope of the invention as disclosed in the appended claim.

We claim:

In a liquid storage tank having a floating roof, one or more shoes adapted to slidably contact 45 the inner tank walls, and a flexible seal between the roof and the shoes, means for excluding water from the space between the shoes and the tank walls comprising an annular member for holding said flexible seal against the upper portion of the shoes, a plurality of circumferentially spaced resilient brackets attached to said annular member and extending above the shoes, an annular wiper attached to the upper portion of said brackets, said wiper being formed entirely of 50 resilient material having a plurality of annular

finger portions adapted to be urged against the inner tank walls by said resilient brackets with the upper exposed surface of the wiper slanting downwardly and inwardly from its outer tank wall contacting edge to its inner edge, said wiper being adapted to retain said downwardly and inwardly sloping surface under all conditions of movement against the sidewalls of the tank, and an annular flexible sealing member secured in sealing engagement with said wiper and the upper portion of the shoes to seal the space between the wiper and the shoes.
